By his Attorney James J. Sheehy.

UNITED STATES PATENT OFFICE.

CARL A. LINDNER, OF LOUISVILLE, KENTUCKY.

OTTOMAN.

SPECIFICATION forming part of Letters Patent No. 388,887, dated September 4, 1888.

Application filed May 21, 1888. Serial No. 274,518. (No model.)

To all whom it may concern:

Be it known that I, CARL A. LINDNER, a citizen of the United States, residing at Louisville, in the county of Jefferson and State of Kentucky, have invented certain new and useful Improvements in Ottomans; and I do declare the following to be a full, clear, and exact description of the invention, such as will enable others skilled in the art to which it applies to make and use the same.

This invention has relation to a convertible ottoman and crib; and it has for its object to provide a cheap and durable means whereby an ottoman may be readily converted into a crib without any apparent alteration of the parts. These objects I accomplish by the means shown and illustrated in the accompanying drawings, in which—

Figure 1 is a perspective view of the device, showing the parts extended so that it may be made into an ottoman and a double or single rail crib. Fig. 2 is a view of one of the locking links or arms, and Fig. 3 is a detail sectional view of one of the hinge-joints.

Referring by letter to the said drawings, A indicates the main frame, which is hollow and in outline of the form of an ottoman, such as may be at present in use, having a skirted or fringe, such as shown. This main frame is provided at one end with a foot rest, B, which is composed of a lower fixed section, a, secured to the upper edge of one of the transverse end walls of the main frame, and an upper hinged section, b, which is hinged to the outer longitudinal edge of the said fixed section, as shown, so that it may form a foot-rest. This foot rest has its hinge-section provided with one or two slotted links or arms, C, which are pivoted at their upper ends to the said hinge-section, and provided with a notch in one of the walls at the opposite end, as shown at d, which is designed to engage a stud, D, in the said fixed section. By this means it will be seen that when the device is used as a crib the foot-rest may be thrown up and held in such position.

E indicates the seat, which is upholstered in the usual manner and has at one end a fixed pillow or head rest, F. This seat is hinged to the opposite end wall of the main frame at its upper edge, so that it may be raised in the

position shown in Fig. 1 for the folding and unfolding of the bed-rails, as will be presently explained. This seat has slotted connections notched and working over studs for holding it elevated similar to that of the hinge-section of the foot-rest.

G indicates the folding crib-rails, there being one hinged to the upper edge of each side wall of the main frame, the form of hinge being better shown in Fig. 3 of the drawings. It will be observed that these rails G are adapted to fold within the main frame or case, which latter may serve as a convenient receptacle for bed-clothing and the like, and that when turned outwardly in a vertical position the seat may be let down to close the opening of the case.

In some cases, when it is desirable, but one of the side rails or sections, G, may be turned out, which will not interfere with the other in any manner whatever.

This device may be cheaply manufactured and at a cost slightly greater than that of the ottoman at present in use.

I am aware of German Patent No. 27,306, in which a sofa bath-tub is shown with a rack attached to one side of the main frame, so that it may be used as a towel or clothes rack when the tub is in use.

Having described my invention, what I claim is—

1. A convertible ottoman and crib, consisting of a hollow frame, hinged rails adapted to fold therein, a hinged seat carrying a head-rest, and the hinged foot-rest secured to the frame, substantially as specified.

2. The combination, with a hollow frame, of the hinged side rails adapted to fold within the frame, a fixed foot rest having a hinged section, a seat hinged to the main frame and carrying a head-rest, studs secured to the said frame, and slotted and notched links pivoted to the seat and foot-rest and adapted to engage the studs in the said frame, whereby the parts may be locked in an elevated position, substantially as specified.

In testimony whereof I affix my signature in presence of two witnesses.

CARL A. LINDNER.
